UNITED STATES PATENT OFFICE

OSCAR W. ANDERSEN, OF OAK PARK, ILLINOIS, ASSIGNOR TO PETTIBONE MULLIKEN COMPANY, OF CHICAGO, ILLINOIS, A CORPORATION OF DELAWARE

ABUTMENT-EQUIPPED ROD

Application filed March 6, 1929. Serial No. 344,861.

My invention relates to rods provided with abutments thereon, serving, more especially as stop means, as for example in spring switch constructions and my object, generally stated, is to provide a novel, simple and inexpensive construction of abutment means which may be quickly and economically assembled with a rod and be held thereon against accidental displacement.

Referring to the accompanying drawings, in which I have illustrated my invention as embodied in an abutment-equipped rod forming an element of a spring switch:

Figure 1 is a longitudinal sectional view of such a switch mechanism in which my invention is embodied.

Figure 2 is a view in longitudinal section showing the detail of the abutment-equipped rod.

Figure 3 is a face view of one of the parts of the device of Fig. 2.

Figure 4 is a similar view of a sectional ring member forming another part of the device; and

Figure 5, a fragmentary sectional view of the two rings forming the abutment device.

Referring to the particular construction shown, the switch mechanism is of the same construction as that shown in my pending application for United States Letters Patent Serial No. 271,884, filed April 21, 1928, and therefore a general description thereof will suffice.

The switch mechanism shown comprises a cylinder 6 for liquid, as for example oil, adapted at its end portion 7 for connection with a bar (not shown) connecting the switchpoints together. Slidable lengthwise in the cylinder 6 is a rod 8 adapted for connection at its end 9 with a switch-stand (not shown). In the particular construction shown the switchpoints may be set to cooperate with either of the main rails at which it is located, such setting being effected by manipulating the switch-stand.

Slidably mounted on the inner end of the rod 8 between abutments 10 thereon, are pistons 11 with a coil spring 12 interposed

between, and abutting at its ends against, these pistons.

In one set position of the switch-stand one of the pistons 11 engages with one end of the cylinder forming a stop therefor and the other piston is engaged by the adjacent abutment device 10, with the spring 12 in compressed condition and the switchpoints set against one of the main rails of the track for holding this switchpoint yieldingly in such position and permitting of the trailing of the wheels therethrough in the movement of a train from the switch track to the main track.

In the other set position of the switch-stand the last-referred-to piston abuts against the other end of the cylinder 6 and the other abutment 10 engages the other piston placing the spring under compression in which position of the parts the other switchpoint is yieldingly pressed against the other main rail permitting of trailing through.

The abutments 10 on the rod 8 are constructed in accordance with my invention and as they are of the same construction the description will be limited to one thereof.

The abutment 10 is formed of a pair of substantially semicircular ring sections 13 positioned in an annular groove 14 in the rod 8, and a ring 15 surrounding the rod 8 and the sections 13 as shown in Fig. 2 holds the latter in place. The ring 15 is provided with an inwardly extending flange 16, intimately embracing the periphery of the rod which limits outward movement of the ring 15 on the rod 8, the flange-equipped end of the ring 10 opposing the portion of the piston 11 with which it cooperates in performing the abutment function.

The ring 10 is held in place sufficiently tightly to prevent accidental displacement from the ring sections 13. This may be effected by making a driving fit between the ring 10 and the ring sections 13, but preferably the end of the ring opposite that provided with the flange 16 extends beyond the adjacent end of the ring 13 and is deflected inwardly into overlapping relationship to the ring as shown at 17, as for example by peening it over against the end of the ring sections 13.

In Fig. 5 I have illustrated by dotted lines the form of the terminal end portion of the ring 15 before assembly with the ring sections 13 and the rod 8, and by full lines the position to which this end of the ring is deflected as stated.

While I have illustrated and described a particular construction embodying my invention, I do not wish to be understood as intending to limit it thereto as the same may be modified and altered without departing from the spirit of my invention.

What I claim as new, and desire to secure by Letters Patent, is:

15 An abutment-equipped rod structure comprising a rod having a peripheral recess, a split ring disposed in said recess projecting outwardly beyond the latter, a ring surrounding said split ring and holding the same in
20 said recess, the second mentioned ring having a flange at one end adapted for direct abutment with a piston or the like, said flange at one surface thereof intimately contacting with the periphery of the rod and at another surface overlapping one end face of said split ring, and said second ring having an integral portion deflected inwardly at the end opposite the said flange and overlapping the other end face of said split ring.

30 OSCAR W. ANDERSEN.
